Term of patent 3½ years

(Cl. D33—14)

To all whom it may concern:

Be it known that I, Paul W. Moyer, a citizen of the United States, residing at Maryville, in the county of Nodaway and State of Missouri, have invented a new, original, and ornamental Design for a Television Stand, of which the following is a specification, reference being had to the accompanying drawing, forming a part thereof, wherein:

Fig. 1 is a front elevational view of a television stand, showing my new design.

Fig. 2 is a side elevational view thereof; and

Fig. 3 is a top plan view of a television stand.

I claim:

The ornamental design for a television stand, as shown.
